UNITED STATES PATENT OFFICE.

JOHN C. C. JUSTIS, OF BALTIMORE, MARYLAND.

DESIGN FOR A HANDLE FOR SPOONS, FORKS, &c.

SPECIFICATION forming part of Design No. 20,725, dated May 19, 1891.

Application filed April 17, 1891. Serial No. 389,380. Term of patent 3½ years.

To all whom it may concern:

Be it known that I, JOHN C. C. JUSTIS, a citizen of the United States, residing at Baltimore, in the State of Maryland, have invented and produced a new and original Design for Handles for Spoons, Forks, and Similar Articles, of which the following is a specification, reference being had to the accompanying drawings, forming a part hereof, and wherein—

Figure 1 represents an obverse or front view of my design as applied to the handle of a spoon. Fig. 2 represents a like view of my design as applied to the handle of a fork.

The leading features of my design are the representation of a terrapin at the end of the handle, in conjunction with the representation of a crab and of oyster-shells arranged along the handle and interspersed with seaweed.

In the drawings, A indicates the representation of a terrapin.

B indicates the representation of oyster-shells.

C indicates the representation of a crab, and D indicates the representation of the interspersed seaweed.

What I claim is—

The design for the handle of a spoon, fork, or similar article, as shown.

In testimony whereof I affix my signature in presence of two witnesses.

JOHN C. C. JUSTIS.

Witnesses:

ROSWELL A. DANDARAW,
WM. H. JONES.
